DESIGN FOR A LIGHTER

Miltiades Omirolis, New York, N. Y.

Application September 6, 1944, Serial No. 115,200

Term of patent 7 years

(Cl. D48—27)

To all whom it may concern:

Be it known that I, Miltiades Omirolis, a citizen of the United States, residing at New York, in the county of New York and State of New York, have invented a new, original, and ornamental Design for a Lighter, of which the following is a specification, reference being made to the accompanying drawing, forming a part thereof, in which

Figure 1 is a front elevational view showing a lighter embodying my new design;

Figure 2 is an end elevational view of the lighter shown in Figure 1;

Figure 3 is a rear elevational view of Figure 1;

Figure 4 is the other end elevational view of Figure 1;

Figures 5 and 6 are bottom and top plan views, respectively, of Figure 1;

Figure 7 is a perspective view showing the lighter in a closed position; and

Figure 8 is a similar view showing the lighter in an open position.

I claim:

The ornamental design for a lighter, as shown.

MILTIADES OMIROLIS.
